CLAIM

The ornamental design for a deck plank attachment clip, as shown and described.

DESCRIPTION

FIG. 1 is a perspective view of a deck plank attachment clip, showing my new design;

FIG. 2 is a top view thereof;

FIG. 3 is a bottom view thereof.

FIG. 4 is a side view thereof, the opposite side view being a mirror image; and,

FIG. 5 is an end view thereof, the opposite end view being a mirror image.
